(57) **CLAIM**

The ornamental design for a turbine housing, as shown and described.

DESCRIPTION

FIG. 1 illustrates a perspective view of a turbine housing. FIG. 2 illustrates a left side view of the turbine housing. FIG. 3 illustrates a right-side view of the turbine housing. FIG. 4 illustrates a top view of the turbine housing. FIG. 5 illustrates a bottom view of the turbine housing. FIG. 6 illustrates a front view of the turbine housing. FIG. 7 illustrates a back view of the turbine housing; and, FIG. 8 illustrates a perspective view of the turbine housing shown in environmental use.

The broken lines shown represent environmental subject matter and form no part of the claimed design.
